UNITED STATES PATENT OFFICE.

WILLIAM C. BROWN, OF PRESCOTT, ONTARIO, CANADA.

CENTRIFUGAL AND TURBINE PUMP AND THE LIKE.

984,189.

Specification of Letters Patent. Patented Feb. 14, 1911.

Application filed June 27, 1908. Serial No. 440,665.

To all whom it may concern:

Be it known that I, WILLIAM C. BROWN, a citizen of the United States, residing at Prescott, Province of Ontario, and Dominion of Canada, have invented certain new and useful Improvements in Centrifugal and Turbine Pumps and the Like, fully described and represented in the following specification and the accompanying drawings, forming a part of the same.

The especial object of the present invention is to provide a centrifugal pump by which eddies in the flow shall be avoided and a high efficiency secured.

15 The invention is especially intended for pumps of that class employing a series of impellers, through which the fluid passes successively, and commonly known as multi-stage pumps, but the broader features of the 20 invention may be used in single stage pumps employing one or more impellers. I secure the desired result by passages extending from the outer ends of the diffusing vanes, to the suction of the next impeller or to the 25 delivery of the last impeller if a delivery at the end of the pump be used, these passages being of substantially the same area as the outer ends of the diffusing passages, so as to get substantially the same velocity of 30 flow from the diffusing vanes to the next impeller suction or to the delivery.

In the accompanying drawings forming a part of this specification, the invention is 35 illustrated as applied in its preferred form to a four-stage pump of a well known type, and this construction will now be described in detail and the features forming the invention then specifically pointed out in the claims.

40 In the drawings, Figure 1 is a vertical longitudinal central section of the pump on the line 1 of Fig. 2. Figs. 2, 3 and 4 are cross sections on, respectively, lines 2, 3 and 4 of Fig. 1.

45 Referring to the drawings, A are the impellers, shown as of the usual closed impeller type, B the shaft carrying the impellers, and C, D the suction and delivery at opposite ends of the pump. The impeller is 50 shown as having the usual curved vanes, 1, and balancing openings 2 through the hub, but these features are not essential. The casing is formed by the suction head E, the delivery head F and the outside casing G, 55 within which are mounted on the shaft the partition sections H and diffusing rings I,

carrying the diffusing vanes 10, forming the diffusing passages 11, all as well known in such pump constructions.

Referring now to the present invention, 60 the casing G has the interior ribs or vanes 12 extending from the outer ends of the diffusing vanes 10 to the ribs or vanes 13 on the partitions, the ribs or vanes 12, 13 forming passages 14 extending from the 65 outer ends of the diffusing passages 11 substantially to the suction of the next impeller in the case of the first and intermediate impellers, the vanes 12 being preferably formed integral with the casing G and the 70 vanes 13 integral with the partition sections H, although this method of construction is not essential. In the construction shown, six diffusing passages 11 and corresponding 75 passages 14 are shown, but it will be understood that this number may be varied.

The stationary vanes 13 are shown in Fig. 3 as diverging somewhat, so that the dimensions of the passages 14 transversely to the pump increase somewhat toward the center 80 of the pump. This construction is preferable, so as to form a narrow meeting surface of adjacent vanes 13 at the center, as otherwise flat surfaces surrounding the impeller suction would be formed, permitting eddies 85 at the center of the pump. As shown, the vanes 13 of adjacent passages are brought substantially to a meeting line 4. As shown in Fig. 1, the side walls of the passages 14 converge toward the center so as to reduce 90 the dimensions of the passages longitudinally of the pump, and thus compensate for the increase of the other dimensions and secure the passage area desired.

If a central delivery of the last impeller 95 be used, the construction preferably will be the same as with the first and intermediate impellers, and it will be understood that the last impeller may deliver from the diffusing 100 passages 11 through the ordinary annular chamber surrounding the diffusing ring. A preferred form of delivery is shown, however, with the delivery D in the head F at one side of the center, which involves some 105 change from the construction shown in connection with the other impellers, in that the stationary vanes 15 in the head F and passages 16 between them, corresponding to the vanes 13 and passages 14, are of varying 110 length and construction, so as to converge at the delivery D. A guiding cone 3 is preferably used on the last partition H opposite

the delivery D to guide the fluid from the passages 15 to the delivery without forming eddies.

While the invention is especially intended for use in centrifugal pumps for liquids, it may be used also in blowers and the like for gaseous fluids, and by reversal the invention may be applied also in motors if desired, and such uses are within the invention.

It is to be understood that the invention is not to be limited to the exact form or arrangement of the passages shown, nor to the special class or details of construction of the pump illustrated, but that all these may be varied while retaining the invention as defined by the claims.

What is claimed is:—

1. A centrifugal pump, blower, or the like, having diffusing passages surrounding the impeller and corresponding passages of substantially uniform area continuing the diffusing passages to the suction of the next impeller or to the pump delivery.

2. In a multi-stage centrifugal pump, blower, or the like, an impeller having curved diffusing passages surrounding the impeller and delivering radially, and corresponding passages of substantially uniform area connecting the diffusing passages with the suction of the next impeller.

3. In a multi-stage centrifugal pump, blower, or the like, a series of impellers having diffusing passages surrounding the impellers, corresponding passages of substantially uniform area connecting the diffusing passages of the first and intermediate impellers with the suction of the next impeller, and corresponding passages of substantially uniform area connecting the diffusing pas-

4. In a multi-stage centrifugal pump, blower, or the like, a series of impellers having diffusing passages surrounding the impellers, corresponding passages of substan-

tially uniform area connecting the diffusing passages of the first and intermediate impellers with the suction of the next impeller, and corresponding passages of substantially uniform area connecting the diffusing passages of the last impeller with the delivery, said delivery being placed at the end of the pump on one side of the center.

5. In a multi-stage centrifugal pump, blower, or the like, a series of impellers having diffusing passages surrounding the impellers, corresponding passages of substantially uniform area connecting the diffusing passages of the first and intermediate impellers with the suction of the next impeller, corresponding passages of substantially uniform area throughout connecting the diffusing passages of the last impeller with the delivery, said delivery being placed at the end of the pump on one side of the center, and a guide cone 3 in the delivery.

6. A centrifugal pump, blower, or the like, having diffusing passages surrounding the impeller, a delivery longitudinal of the impeller shaft and on one side of the center, and corresponding passages of substantially uniform area connecting the diffusing pas-

7. A centrifugal pump, blower, or the like, having diffusing passages surrounding the impeller, a delivery longitudinal of the im- 75 peller shaft and on one side of the center, corresponding passages of substantially uniform area connecting the diffusing passages with the delivery, and a guide cone 3 in the delivery.

In testimony whereof, I have hereunto set my hand, in the presence of two subscribing witnesses.

WILLIAM C. BROWN.
